UNITED STATES PATENT OFFICE.

THOMAS G. McNEILL, OF LUDLOW, CALIFORNIA.

RAILWAY-TRACK.

1,126,538.

Specification of Letters Patent.

Patented Jan. 26, 1915.

Application filed June 10, 1914. Serial No. 844,244.

To all whom it may concern:

Be it known that I, THOMAS G. McNEILL, a citizen of the United States, residing in Ludlow, Stagg P. O., in the county of San Bernardino and State of California, have invented a new and Improved Railway-Track, of which the following is a full, clear, and exact description.

My invention relates to a means for holding track rails in a manner to prevent creeping of the track, or of either rail thereof, my improved rail-holding means, moreover, being formed and positioned to prevent destruction of the same by expansion or contraction of the rails.

In carrying out the invention, a rail-engaging element is provided, of a width to be received between the rails and to lie at opposite sides adjacent to the respective rails, and provided with flanges conforming to the flanges and webs of the rail. The said element is preferably in the form of an annulus which gives the necessary strength with a minimum weight of material. Suitable fastening means are provided to secure the element to the rails. The annulus is secured also to the ties and has associated therewith elongated bars ranging lengthwise of the track between the rails in opposite directions from the annulus, said bars being properly fastened to the ties.

The invention will be more particularly explained in the specific description following.

Reference is to be had to the accompanying drawings forming a part of this specification, in which similar characters of reference indicate corresponding parts in all the views.

Figure 1 is a plan view of a section of railway track having my invention embodied therein; Fig. 2 is a longitudinal vertical section on an enlarged scale; Fig. 3 is a separate fragmentary plan view of the track-holding means; Fig. 4 is a transverse vertical section through one of the rails and the adjacent portion of my improved track-holding device; and Fig. 5 is a fragmentary side view showing a means outside of the rail for fastening my improved rail-holding device.

In constructing a track embodying my invention, a central element 10 is provided, preferably in the form of a flat ring having a diameter to be received between the track

rails A on top of the ties B. The said ring is flattened at the sides and provided with upturned flanges to lie parallel with and adjacent to the rails, at the inside of the latter. The said flanges are shaped to conform to the flange and web of the rail. Thus an inclined member 11 is adapted to overlie the rail flange, and the vertical member 12 is adapted to lie adjacent to the web of the rail. The flanges thus formed on the ring 10 and composed of the members 11 and 12 are secured in position by elongated straps 13, 14, at the inside and outside of the rail, respectively, and bolts extend transversely to the said straps through the rail and through the upright flange member 12. Nuts 16 on the bolts 15 complete the connection. The outer strap plate 14 is thickened at the upper edge to provide a longitudinal rib 14^a beneath which the bolt head 15^a is received and prevented from turning.

In order to firmly secure the ring 10 to the ties B, holes 17 are provided to receive lag screws 18 to engage the ties therebeneath between the track rails. The holes 17 receive the plain necks of the lag screws, while the threads of the screws enter the ties, the said lag screws being of a known form having the plain necks as specified. Thus the ring is directly secured to the ties at approximately diametrically opposite points on the ring.

Associated with the ring 10 are elongated bars 19, extending in opposite directions from the ring at diametrically opposite sides and ranging lengthwise of the track, midway between the rails. The said bars 19 are preferably formed of half-inch boiler plate approximately six inches wide, and are secured to the ring 10 by bolts 20 and to the ties by lag screws 21.

The rings with their bars 19 are in practice secured throughout the whole length of the track at intervals of, say, five hundred or one thousand feet, and each ring 10 is positioned between the ends of the rails and not at the joints, the arrangement being designed to minimize the disruptive tendency of expansion and contraction in the rails, as well as to prevent creeping of the rails.

Having thus described my invention, I claim as new and desire to secure by Letters Patent:

1. The combination with a railway track

- comprising rails and ties, of a rail-holding means comprising an element extending transversely between the rails and fastened to said rails, and means for securing said element to the ties, said last mentioned means comprising elongated bars rigidly secured to said element and ranging lengthwise of the track, said bars being fastened to the ties.
- 10 2. A holding means for track rails, comprising an annulus having a diameter to be received between the track rails with its sides adjacent to said rails, means fastening the annulus to the respective rails, and means for fastening the annulus to the ties.
3. A holding-means for track rails, comprising an annulus having a diameter to be received between the track rails with its sides adjacent to said rails, means for fastening the annulus to the respective rails, and means for fastening the annulus to the ties, said last mentioned means comprising elongated bars extending in opposite directions from the annulus, and connected with the latter.

4. A holding-means for track rails, comprising an annulus of a diameter to be received between track rails, and formed with flanges adapted to lie adjacent to and parallel with the webs of the rails, straps at 30 opposite sides of the rails, the inner straps overlying the flanges of the annulus, bolts securing the said straps and flanges to the rails, the said outer straps having beads engaging the heads of the bolts, lag screws 35 directly securing the said annulus to the ties beneath the same at approximately diametrically opposite sides of the annulus between the rails, elongated bars extending in opposite directions from the annulus and 40 ranging longitudinally of the track between the rails, and lag screws securing said bars to the ties.

In testimony whereof I have signed my name to this specification in the presence of 45 two subscribing witnesses.

THOMAS G. McNEILL.
